UNITED STATES PATENT OFFICE.

BURL BRANCH, OF TORONTO, ONTARIO, CANADA.

BARKING DRUM.

Application filed September 19, 1927, Serial No. 220,459, and in Canada March 24, 1927.

This invention relates to barker drums for removing the bark from logs which are to be made up into paper pulp. Heretofore these drums have been constructed of bars and rings secured together by means of rivets and bolts having their axes directed radially of the drum and having their heads located within the interior of the drum, and my object is to provide a drum of simple construction that will overcome the above objectionable features.

I attain my object by providing inwardly directed lugs on rings by means of which the drum is carried so that it may be rotated. The rings are connected by means of longitudinal channel bars which are mounted between adjacent lugs on the rings. The flanges of the channel bars are directed outwardly and a rivet or bolt is passed through each lug and the flanges of adjacent bars in contact therewith. The constructions are hereinafter more fully described and are illustrated in the accompanying drawings in which:

Fig. 1 is a side elevation of a portion of an end section of my drum;
Fig. 2 a cross sectional detail of the drum;

Fig. 3 a view similar to Fig. 2 on a larger scale showing the means for securing the bars to the rings; and

Fig. 4 a longitudinal sectional detail of the drum showing the binding ring and driving gear connected thereto in cross section.

In the drawings like letters of reference indicate corresponding parts in the different figures.

The drum includes a plurality of rings A and a plurality of longitudinal channel bars B which define the circumference of the drum. The rings are provided with radial lugs C which are directed inwardly between adjacent bars to space them from one another. The flanges b and b' of the channel bars are directed outwardly and are adapted to be received snugly between adjacent lugs C to form a number of continuous bands of metal therewith around the drum. Rivets D are passed through the lugs and through the flanges b and b' of the adjacent channel bars in contact with each lug secure the bars to the lugs. The axes of the rivets are directed substantially circumferentially of the drum and substantially at right angles to the axis thereof. The outer ends of the flanges b and b' engage shoulders c' formed on the lugs C.

From the above description it is obvious

that the rivets D merely hold the bars B in position on the lugs C and that any stresses, caused by the logs striking the bars, are borne by the shoulders or the lugs. In other words the hereinbefore described arrangement for securing the bars to the rings substantially eliminates any shearing stress on the rivets. Further the rivets are so located that they cannot be struck by the logs tumbling around within the drum and therefore they will not be damaged nor loosened by the logs.

The spaces E between the longitudinal bars form slots through which the detached pieces of bark may discharge from the drum into the tank or the like (not shown) wherein the drum is mounted. The drum is suitably supported for rotation by rollers or pulleys (not shown) which engage the peripheries of the rings A and is suitably driven by means of a pinion (not shown) meshed with a gear G secured by studs H to the side of one of the rings A.

Any number of rings A may be used in accordance with the length of the drum and the bars intermediate the rings may be connected in spaced relationship with one another by means of blocks I fitted in the spaces E. The blocks are connected by rivets J to adjacent flanges b and b', the rivets J being arranged in the same manner as the rivets D.

It will be distinctly understood that the term "rings" used throughout the claims is intended to include any members for supporting the longitudinal bars of a barker and that the term "rivets" includes bolts and the like.

What I claim is:

1. A barking drum comprising rings connected by longitudinal bars, the rings being provided with lugs directed between adjacent bars.

2. A barking drum comprising rings; a plurality of longitudinal bars defining the circumference of the drum, the rings being provided with lugs directed inwardly between adjacent bars; and means for securing the bars to the lugs.

3. A barking drum comprising rings; a plurality of longitudinal bars; lugs carried by the rings; and rivets for securing the bars to the lugs, the said rivets having their axes directed substantially circumferentially of the drum and substantially at right angles to the axis thereof.

4. A barking drum comprising a series of channel bars; binding rings provided with lugs directed inwardly between adjacent bars to space them from one another; and 25
rivets for securing the bars to the lugs, the said rivets having their axes directed substantially circumferentially of the drum and substantially at right angles to the axes thereof.
5. A barking drum comprising rings; a plurality of longitudinal channel bars defining the circumference of the drum, the flanges of the channel bars being directed outwardly; lugs carried by the rings, the 30
said lugs being directed inwardly between the flanges of adjacent channel bars; and a rivet passed through each lug and the flanges adjacent thereto.
6. A barking drum comprising rings; a plurality of longitudinal channel bars defining the circumference of the drum; lugs directed inwardly from the rings, the lugs being spaced from one another to receive a 35
channel bar between adjacent lugs; shoul-
ders formed on the lugs for limiting the outward movement of the channel bars; and rivets for securing the channel bars to the lugs.
7. A barking drum comprising rings connected by longitudinal bars, the rings being provided with lugs directed between adjacent bars to space them from one another; and blocks interposed between adjacent bars intermediate the ends thereof.
8. A barking drum comprising a series of channel bars; binding rings provided with lugs directed inwardly between adjacent bars to space them from one another; rivets 40
for securing the bars to the lugs; blocks located in the spaces between the bars; and rivets for securing the blocks to the bars, the first and second mentioned rivets having their axes directed substantially circumferentially of the drum and substantially at right angles to the axes thereof. 45
